Des. 237,802
Patented Nov. 25, 1975

237,802

TELEPHONE PUSH-BUTTON DIAL

Gerhart F. Klaiber, Deal, and Donald Foggia, Oakhurst,
N.J., assignors to TIE/Communications, Inc., Stamford, Conn.

Filed June 3, 1974, Ser. No. 475,851

Term of patent 14 years

Int. Cl. D14—03

U.S. Cl. D26—14 A

FIG. 1 is a perspective view of a telephone push-button dial according to the new design.

FIG. 2 is a top plan view of the dial of FIG. 1.

FIG. 3 is an elevation view of the dial of FIG. 1 as viewed in the direction of arrow 3 in FIG. 2.

FIG. 4 is an elevation view of the dial of FIG. 1 as viewed in the direction of arrow 4 in FIG. 2.

FIG. 5 is an elevation view of the dial of FIG. 1 as viewed in the direction of arrow 5 in FIG. 2.

FIG. 6 is an elevation view of the dial of FIG. 1 as viewed in the direction of arrow 6 in FIG. 2.

FIG. 7 is a bottom plan view of the dial of FIG. 1.

FIG. 8 is a sectional, elevation view as viewed along lines 8-8 shown in FIG. 2.

We claim:

The ornamental design for a telephone push-button dial, as shown and described.
